UNITED STATES PATENT OFFICE.

GEORG CARL BRACKLOW, OF ELMSHORN, GERMANY.

COOLING MEANS FOR EXPLOSIVE-ENGINES.

SPECIFICATION forming part of Letters Patent No. 615,672, dated December 13, 1898.

Application filed September 27, 1897. Serial No. 653,149. (No model.)

To all whom it may concern:

Be it known that I, GEORG CARL BRACKLOW, residing at Elmhorn, near Hamburg, Muhlenstr., in the Empire of Germany, have 5 invented certain Improvements in Gas-Motors, (for which I have obtained a patent in Great Britain, No. 16,399 of 1897,) of which the following is a specification.

My invention relates to a novel arrangement of the cylinder and piston in gas, benzine, and similar motors for the purpose of maintaining a constant circulation of a cooling medium by the action of the piston and at the same time effecting a perfect explosion 15 and facilitating the lubrication of the working parts. My arrangement of the working parts also insures cleanliness of the motor.

My invention is represented in the accompanying drawings, in which—
20 Figure 1 shows a vertical sectional view of a gas-motor made according to my invention. Fig. 2 is a horizontal sectional view of the same.

The explosion-chamber *a*, of approximately trumpet shape, is open at its forward end and has at its rear end, as usual, the gas admission and eduction valves (shown, but not specifically described) and is inclosed by a cylindrical jacket *j*, forming, with the wall 25 of the explosion-chamber, a cooling space or chamber *a'*, closed at the front by the flaring wall of chamber *a*. The accurately-turned outer surface of the jacket *j* of the explosion-chamber is formed with annular grooves to receive the usual springy, packing-bands *c*, upon which works the hollow working piston *b*, hereinafter more fully described.

d is a cylindrical jacket surrounding and supported concentric to the jacket *j* of the 30 explosion-chamber and forming therewith a cooling-chamber *e*, having a valved admission-passage *v* communicating with any suitable supply of a cooling medium, such as air, water, or other fluid. The outer cooling-chamber *e* also communicates with the inner cooling-chamber *a'* through suitable ports *m*, and the chamber *a'* communicates through tubes *o* with an annular outlet-chamber *p*, having valved outlet-passage *s*, the tubes *o* 35 being extended forward into chamber *a'* a sufficient distance to insure the circulation of the cooling medium (entering through ports

m from chamber *e*) through the entire cooling-chamber *a'* before it passes out through tubes *o*, space *p*, and valved passage *s*. To 55 insure the circulation of the cooling medium through the entire cooling-chamber *e*, the inlet-passage *v* is arranged near the forward end of the chamber *e*, while the outlet-ports *m* are adjacent to the rear end of said chamber, and, furthermore, the action of the piston draws the cooling fluid to the front of chamber *e*, as will presently appear.

The hollow working piston *b* covers the open end of the cylinder and has a cylindrical 65 enlargement *b'*, forming a subpiston which works snugly within the outer jacket *d*, the jacket *d* forming the cylinder and subpiston *b'* the piston of a pump which effects the constant circulation of the cooling medium 70 through the two cooling-chambers and passages above described. The cooling-chambers *a'* and *e* are isolated from the explosion-chamber *a*, and the cooling fluid passed through said chambers cannot enter the explosion-chamber, but serves only for keeping 75 the working parts of the motor cool.

The inlet *x*, leading to chamber *p*, (represented in dotted lines in Fig. 1,) may also be used to admit the cooling medium to the cooling-chambers when a liquid is employed, in which case the cooling liquid would first pass into chamber *a'* through tubes *o* and then into chamber *e* through ports *m* when the piston *b'* moves forwardly, and would be forced out 85 through said chambers and passages in the reverse order when the piston *b'* moves back.

The chief advantage resulting from my improved form of motor is the effective cooling 90 of the working parts by the continuous circulation of the cooling medium through the cooling-chambers, each stroke of the piston causing a complete change of the cooling medium in the chambers. The great length 95 of the trumpet-shaped explosion-chamber, which serves also as the mixing-chamber, produces a perfect mixture of the air and gas and an effective explosion of the same, which is utilized to its utmost capacity. By reason of the arrangement of the hollow piston surrounding the explosion-chamber and sliding upon its jacket *j* the parts can be effectively kept oiled, and all of the parts are so confined 100 within the jackets that little or no dirt will

enter to interfere with the smooth working of the motor.

The motor may be worked with any of the known explosive mixtures of air with hydrocarbon gases or liquids.

Having thus described my invention, what I claim, and desire to secure by Letters Patent, is—

1. In a gas engine or motor, the combination of the engine-cylinder and the working piston, of a cooling-chamber surrounding the engine-cylinder and isolated from the explosion-chamber, and a subpiston attached to the engine-piston and operating to cause a circulation of a cooling medium through the cooling-chamber, substantially as set forth.
2. In a gas engine or motor, the combination of the engine-cylinder and the working piston, a cooling-chamber surrounding and isolated from the engine-cylinder, valved inlet and outlet passages leading to and from said cooling-chamber, and a subpiston forming part of the main piston and working in the cooling-chamber to draw the cooling medium into and expel it from said chamber, substantially as set forth.
3. In a gas engine or motor, the combination of the open-ended engine-cylinder, the hollow working piston inclosing the open end of the cylinder, a cooling-chamber surrounding the engine-cylinder, and isolated from the combustion-chamber, valved inlet and outlet passages to and from the cooling-chamber, and a subpiston forming part of the working piston and adapted to circulate a cooling medium through the cooling-chamber, substantially as set forth.
4. In a gas engine or motor, the combination

of the open-ended engine-cylinder, the hollow working piston inclosing the engine-cylinder and covering its open end, a cooling-chamber surrounding the engine-cylinder and within the working piston, a second cooling-chamber surrounding the first cooling-chamber and the working piston, said cooling chambers being isolated from the combustion-chamber and in communication with each other, a subpiston on the working piston operating in said second cooling-chamber, and inlet and outlet passages to and from the cooling-chambers, substantially as set forth.

5. In a gas engine or motor, the combination of the open-ended engine-cylinder, the working piston inclosing the engine-cylinder and covering its open end, a cooling-chamber surrounding the engine-cylinder and located within the working piston, outlet-passages leading from the cooling-chamber adjacent to its forward end to an outlet-chamber for the cooling medium, a second cooling-chamber surrounding the first cooling-chamber and working piston, an inlet for the cooling medium entering the second cooling-chamber adjacent to its forward end, ports communicating between the cooling-chambers adjacent to their rearends, and a subpiston formed on the working piston and operating in the second cooling-chamber, substantially as and for the purpose set forth.

In witness whereof I have hereunto set my hand in presence of two witnesses.

GEORG CARL BRACKLOW.
